UNITED STATES PATENT OFFICE.

DANIEL JOSEPH WALSH, OF PITTSFIELD, MASSACHUSETTS.

EXCAVATING MACHINE.

Application filed March 23, 1925. Serial No. 17,719.

To all whom it may concern:

Be it known that I, DANIEL JOSEPH WALSH, a citizen of the United States, residing at Pittsfield, in the county of Berkshire and State of Massachusetts, have invented certain new and useful Improvements in Excavating Machines, of which the following is a specification.

This invention relates to excavating machines, and more particularly to dippers therefor.

An object of the invention is the provision of an improved dipper and dipper lid, together with operating means for the lid.

A further object is to provide a construction in which a portion of the lid serves to force the material from the dipper when the lid is swung on its pivot.

A further object of the invention is the provision of means for adjusting the angle of the shovel to the dipper stick.

In the accompanying drawings, I have shown one embodiment of the invention. In this showing:

Figure 1 is a side elevation of the dipper stick and dipper showing a portion of the main boom,

Figure 2 is a horizontal sectional view on line 2—2 of Figure 1,

Figure 3 is a similar view on line 3—3 of Figure 1,

Figure 4 is a side elevation of the dipper stick and dipper in an inclined position showing, in dotted lines, the lid in open position,

Figure 5 is a horizontal sectional view on line 5—5 of Figure 4,

Figure 6 is a vertical sectional view on line 6—6 of Figure 5, and,

Figure 7 is a perspective view of the dipper lid.

Referring to the drawings, the reference numeral 1 designates the main boom of an excavating machine which is provided with a bracket or support 2 for a shipper shaft 3, which carries a pinion 4. A dipper stick 5 is mounted at an angle to the main boom and is provided with a rack 6, which meshes with the pinion 4 to permit movement of the dipper stick relative to the boom. The dipper stick may also be swung at an angle about the shipper shaft 3 by means of a flexible

cable (not shown) secured to the dipper stick adjacent its lower end in the usual manner. As shown (see Figures 2 and 3) the dipper stick is formed of a pair of angle irons 7, which are spaced from each other and connected at intervals by means of webs 8.

A dipper is mounted on the lower end of the dipper stick. As shown, the dipper comprises a bottom 9 and side walls 10. The bottom may be provided with longitudinally extending members 11 projecting beyond the front edge of the dipper to assist in digging. A plate 12 is secured to the side walls and this plate is twisted and extends across the top of the dipper, as at 13. Similarly, a strap 14 is secured to the side walls and is provided with a portion 15 extending across the top and parallel to the extension 13. The members 13 and 15 are adapted to support a pair of longitudinally extending members 16 adjacent each side of the dipper. The lower end of the dipper stick is provided with ears 17 adapted to receive pins 18 which extend through the longitudinally extending member 16 to pivotally support the dipper on the dipper stick. A strap 19 is secured to each side of the dipper stick adjacent the bottom and extends downwardly at an angle. The lower ends of these straps are provided with openings adapted to receive pins 20, which also extend through the members 16 adjacent their rear ends. As shown, the straps are provided with a plurality of openings 21 adjacent their upper ends, and a bolt 22 is adapted to be received in a selected opening in the strap and in the dipper stick to support the dipper at a desired angle.

Each of the side walls of the dipper is provided with an inclined reenforcing strip 23 adjacent its rear end. The dipper lid consists of a substantially L-shaped member having a top 24 adapted to be arranged beneath the transverse members 13 and 15, and this top is extended at right angles to form a back plate 25, which normally closes the rear of the dipper. As shown, a reenforcing plate 26 may be arranged on the interior of the plate 25 and transverse reenforcing members 27 may be arranged on the exterior. The lid is further provided with triangular shaped side walls 28, the forward

edges of which are adapted to engage the strips 23 when the lid is in closed position (see Figure 1). Ears 29 are formed at the upper forward ends of the side walls and 5 these ears are adapted to be connected to links 30, the opposite ends of which are connected to an auxiliary boom 31 which is movably mounted with respect to the dipper stick and by means of which the lid may be 10 swung to an open position. The top of the lid is also provided with ears 32 which are provided with openings 33 adapted to receive the pins 20 to form a fulcrum for the lid and permit it to swing when the auxiliary boom 31 is actuated.

The auxiliary boom consists of a pair of side plates 34 (see Figures 2 and 3) connected to each other at intervals by webs 35 and plates 36 are arranged on the exterior 20 of the side plates 34. These plates are provided with rack teeth 37. An engine 38 is mounted on the dipper stick adjacent its lower end and is provided with a flexible conduit 39 leading to the operator's platform or cage. This conduit is provided 25 with a suitable valve (not shown) by means of which the engine may be controlled. The engine is provided with a connecting rod 39, which is connected to the crank portion 40 of a shaft 41. The shaft 41 is mounted in suitable bearings 42 on the side of the dipper stick and is provided with a pinion 43 at each end. These pinions are adapted to 30 mesh with gears 44 arranged on opposite sides of the dipper stick and carried by a shaft 45. The shaft 45 is in turn provided with pinions 46, meshing with racks 37 to 35 permit the auxiliary boom 31 to be moved with respect to the dipper stick. As shown, 40 suitable guides 47 are secured to the dipper stick and extend around the auxiliary boom to retain it in position.

In operation, the angle of the shovel with 45 respect to the dipper stick is adjusted by means of the spaced openings 21 in the arms 19. The dipper stick is actuated in the usual manner by means of the gear 4 and rack 6 and is swung around the shipper shaft 3 as a pivot in the usual manner, to the desired 50 angle. When the lid is to be opened, the auxiliary boom is moved upwardly by means of the engine 38 and the gear connecting the shaft 41 to the racks 37. This raises the links 30 and moves the rear end of the lid 55 upwardly to the dotted line position shown in Figure 4 of the drawings. The width of the lid is slightly less than the distance between the side walls 10 of the dipper and this permits the forward end of the lid to 60 swing downwardly into the dipper, as indicated in dotted lines in Figure 4 of the drawings. The length of the dipper lid forwardly of the ears 32 is sufficient to permit the forward end to scrape the bottom of the dipper and this facilitates the removal of

muddy or sticky material from the dipper. As shown, the forward end of the lid is curved upwardly as at 48, which acts as a baffle to prevent the material being dug from passing over the top of the dipper and 70 collecting on the lid between the transverse members 13 and 15 and the longitudinal members 16. These members limit the upward movement of the forward end of the lid when it is returned to normal position. 75 A transverse member 49 is arranged between the side walls of the dipper and is adapted to be engaged by the rear portion of the lid to limit its downward movement. The lid is returned to normal position by reversing 80 the direction of movement of the shaft 41 and its associated parts.

It is to be understood that the form of my invention herewith shown and described is to be taken as a preferred example of the 85 same, and that various changes in the shape, size, and arrangement of parts may be resorted to without departing from the spirit of the invention or the scope of the subjoined claims. 90

I claim:

1. In an excavator, a dipper stick, a dipper mounted on the end of said dipper stick, a lid pivotally mounted on said dipper, guides arranged on said dipper stick, an auxiliary boom mounted in said guides and movable with respect to said dipper stick, connections between said auxiliary boom and said lid, a rack carried by said auxiliary boom, and a pinion meshing with said rack. 100

2. In an excavator, a dipper stick, a dipper mounted on the end of said dipper stick, a lid pivotally mounted on said dipper, guides arranged on said dipper stick, an auxiliary boom mounted in said guides and movable with respect to said dipper stick, connections between said auxiliary boom and said lid, a rack carried by said auxiliary boom, a shaft mounted on said dipper stick, a pinion carried by said shaft and meshing with said rack, and an engine mounted on said dipper stick and operatively connected to said shaft. 110

3. In a device of the character described, a dipper having side walls, a bottom and having an open front, transverse members connecting the upper edges of said side walls, a lid comprising a top and a rear wall, longitudinally extending members connecting said transverse members, and means for pivotally mounting said lid on said longitudinally extending members. 115

4. A device constructed in accordance with claim 3 wherein the portion of the top of said lid forwardly of said pivot is substantially equal to the height of the side wall. 120

5. In a device of the character described, a dipper stick, a dipper carried thereby, said dipper comprising a body portion having 125

side walls, a bottom and having an open front, a lid for said dipper comprising a top and rear wall, longitudinally extending members connected to said body portion and arranged over said top, means for pivotally mounting said lid on said longitudinally extending members, an auxiliary boom carried by said shipper shaft and movable with re-

spect thereto, and connections between said boom and said lid. ¹⁰

6. A device constructed in accordance with claim 5 wherein an engine is mounted on said dipper stick and operatively connected to said auxiliary boom.

In testimony whereof, I affix my signature.
DANIEL JOSEPH WALSH.
